US00D923420S

(12) **United States Design Patent** (10) Patent No.: **US D923,420 S**
(45) Date of Patent: **** Jun. 29, 2021**

(54) **COFFEE CAPSULE TRAY FOR DRAWER**

(71) Applicant: **XIAMEN LEGENDA ELECTRONIC TECHNOLOGY COMPANY LIMITED**, Xiamen (CN)

(72) Inventor: **Wenda Zhong**, Xiamen (CN)

(73) Assignee: **XIAMEN LEGENDA ELECTRONIC TECHNOLOGY COMPANY LIMITED**, Xiamen (CN)

(**) Term: **15 Years**

(21) Appl. No.: **29/719,336**

(22) Filed: **Jan. 3, 2020**

(30) **Foreign Application Priority Data**

Sep. 24, 2019 (CN) 201930524454.2

(51) **LOC (13) Cl.** **07-99**

(57) **CLAIM**

The ornamental design for a coffee capsule tray for drawer, as shown and described.

DESCRIPTION

FIG. 1 is a front perspective view of a coffee capsule tray for drawer, showing my new design;

FIG. 2 is a front view thereof;

FIG. 3 is a back view thereof;

FIG. 4 is a right side view thereof;

FIG. 5 is a top view thereof;

FIG. 6 is a bottom view thereof; and,

FIG. 7 is a rear perspective view thereof.

A left side view is omitted since the right side view is identical to the left side view.

1 Claim, 7 Drawing Sheets
